WINDOW SASH SNUBBER

Filed Aug. 1, 1930

Arthur E. Devol
INVENTOR;
BY *Victor J. Evans*
HIS ATTORNEY.

UNITED STATES PATENT OFFICE

ARTHUR E. DEVOL, OF TINLEY PARK, ILLINOIS, ASSIGNOR OF ONE-HALF TO EDWARD HARTWIG, OF TINLEY PARK, ILLINOIS

WINDOW SASH SNUBBER

Application filed August 1, 1930. Serial No. 472,404.

This invention relates to certain novel improvements in window sash snubbers and has for its principal object the provision of an improved construction of this character which will be highly efficient in use and economical in manufacture.

The salient object of my invention is the provision of a device of the character described herein which will be positive in operation while containing a minimum number of parts.

A further object of the invention is the provision of an improved construction of the character described herein which may be expeditiously attached to the usual type of window sash and which in operating position will provide a device which will prevent the upper and lower window sashes from being opened from the outside while permitting both upper and lower sash to be moved from the inside.

An additional object of my invention is the provision of an improved construction of the character described herein which embodies a construction effectively preventing a person on the outside of a window with which my invention is associated from lowering an object through a partially opened upper sash thereby to unlock the device with intent to move the upper or lower sash.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is a perspective view of a preferred form of construction of my invention shown in operative position on a window sash;

Fig. 2 is a sectional view taken substantially on the line 2—2 in Fig. 1;

Fig. 3 is a perspective detail view of certain units embodied in my device;

Fig. 4 is a perspective view of another unit embodied in the invention; and

Fig. 5 is a perspective view of a replaceable snubber embodied in the invention.

Referring to the drawings wherein a pre-

ferred embodiment of my invention is associated, 10 indicates a window construction with which an upper sash 11 and a lower sash 12 are associated. My invention is mounted on the upper cross piece 13 of the lower sash 12 at one end thereof and adjacent the stop 14, and my invention is associated with the inner face of one stile 15 of the upper sash, in a manner to be described presently.

My improved device includes a base portion 16 which has formed integrally therewith a rightangularly extending flange portion 17 and a substantially triangular-shaped guard 18, the function of which will be made apparent presently. Provided in the base portion 16 are countersunk openings 19 and 20 and a similar opening 21 is provided in the flange portion 17. In the use of my device the base portion 16 is mounted on the upper surface of the top cross piece of the lower sash by means of suitable connecting elements such as wood screws 22 and 23 inserted through the openings 19 and 20 and a similar screw 24 inserted through the opening 21 in the flange portion 17 which projects downwardly over the inner face of the top cross piece 13 of the lower sash.

The base portion 16 includes rolled end portions 25 and 26 providing a space 27 therebetween and in assembling my device there is disposed in the space 27 the rolled end portion 28 of a channel shaped pawl 29. A suitable pin 30 is projected through the portions 26, 28 and 25 and secured therein in any suitable manner such as by riveting. The pawl 29 is substantially triangular in cross section and is preferably formed of one continuous piece of material and includes side portions 31 and 32 which terminate at one end in arcuated faces 33 and 34. Likewise included in the pawl 29 is a top portion 35 and a bottom portion 36. Shoulders 37 and 38 are provided in the top portion 35 and when the pawl 29 is swung into open position, as shown in dotted outline in Fig. 2, these shoulders 37 and 38 engage the rear end portion of the bottom portion 100

17 and thereby prevent the pawl from falling back and marring the lower sash 12.

The end of the pawl 29 opposite the rolled portion 28 is open as indicated at 39. Inserted into the pawl 29 through the open end 39 is a snubber 40 of any suitable resilient and elastic material, preferably rubber or the like. The snubber 40 is substantially triangular in cross section and includes an arcuated face 41. A threaded opening 42 is provided in the side portion 31 of the pawl 29 and a similar aligned opening 43 is formed in the side portion 32. An opening 44 is provided in the snubber 39 and a suitable connecting element such as the machine screw 45 is inserted through openings 43, 44 and 42 to retain the snubber 40 in position in the pawl 29.

My device may be attached at either or both ends of the cross piece 13 of the lower sash, as desired, and it is manifest that when the upper and lower sashes are in closed position, as shown in Fig. 1, or when either or both sashes are in partly opened position, any attempt to lower the upper sash or raise the lower sash, while the snubber 40 is in position as shown in Fig. 1, will cause the face 41 of the snubber to frictionally engage the face of the sash stile 15 and thereby prevent movement of either sash. It is apparent, therefore, that either the upper or the lower sash may be allowed to remain in partly opened position without permitting any further opening of either sash by a person on the outside of the window.

To prevent a person on the outside from lowering any object through the partly opened upper sash in an attempt to engage the snubber 40 or the pawl 29 and thereby throw the pawl and snubber into position as shown in dotted outline in Fig. 2, I provide the guard 18 which prevents the possibility of any object such as a hook or the like being lowered from above, through the partly opened upper sash, into engagement with the pawl 29. When my device is to be used at the right hand end of the sash, as seen from the interior of the window, I provide the guard 18 at the left, or outside, and when the device is intended for use on the left side of the sash I provide the guard 18 at the right side of the pawl.

From the foregoing description of my invention it is manifest that I have provided an improved construction which while being simple in operation and economical in construction will be highly efficient in use. It is likewise apparent from the foregoing description that my improved device permits of convenient and expeditious attachment to any type of window sash and it will be seen that the device may be painted or enameled, or otherwise decorated, to present

an article which will be neat and attractive in appearance.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. In a device of the class described, a pawl, an elastic member in said pawl, said member having a portion projecting from said pawl at one end thereof, means providing detachable connection between said pawl and said elastic member, supporting means for said pawl, said supporting means including a bracket, means providing hinged connection between said pawl and said bracket, and a guard member formed integrally with said bracket, said guard member projecting rightangularly from the main body portion of said bracket, said guard member being disposed adjacent one side of said pawl and extending parallel to said side.

2. In a device of the class described, a pawl, an elastic member in said pawl, said member having a portion projecting from said pawl at one end thereof, means providing detachable connection between said pawl and said elastic member, supporting means for said pawl, said supporting means including a bracket, said bracket including a rectangular shaped main body portion having a rightangularly extending flange portion integral therewith, means providing hinged connection between said pawl and said bracket, and a guard member formed integrally with said bracket, said guard member projecting rightangularly from the main body portion of said bracket, said guard member being disposed adjacent one side of said pawl and extending parallel to said side.

3. In combination with a lower window sash, a pawl, an elastic member in said pawl, said member having a portion projecting from said pawl at one end thereof, means providing detachable connection between said pawl and said elastic member, supporting means for said pawl, said supporting means including a bracket, said bracket including a rectangular shaped main body portion having a rightangularly extending flange portion integral therewith, said main body portion being disposed on the horizontally extending top cross piece of the sash and having openings provided therein whereby to effectuate detachable connection

with the sash, said flange portion extending downwardly along the outer face of the cross piece and having openings provided whereby to effectuate detachable connection with the sash, means providing hinged connection between said pawl and said bracket, and a guard member formed integrally with said bracket, said guard member projecting rightangularly from the main body portion of said bracket, said guard member being disposed adjacent one side of said pawl and extending parallel to said side.

In testimony whereof I affix my signature.

ARTHUR E. DEVOL.
